COTTON SAMPLER FOR COTTON CONDENSERS

George E. Gaus, Washington, D. C., and Victor L. Stedronskey, Leland, Miss., assignors to Henry A. Wallace, Secretary of Agriculture of the United States of America, and his successors in office

Application October 7, 1938, Serial No. 233,774

3 Claims. (Cl. 19—156)

(Granted under the act of March 3, 1883, as amended April 30, 1928; 370 O. G. 757)

This application is made under the act of March 3, 1883, as amended by the act of April 30, 1928, and the invention herein described and claimed, if patented, may be manufactured and used by or for the Government of the United States of America for governmental purposes without the payment to us of any royalty thereon.

This invention relates to new and useful improvements in attachments for cotton gins or condensers and is more particularly concerned with a device designed to produce a truly representative sample of the contents of a bale of cotton upon completion of the conventional process of ginning.

One of the objects of this invention is the provision of a means which may be applied to a cotton condenser for obtaining a continuous uniform ribbon-like separation of cotton lint as it is being formed into a bat on the screen drum cylinder of a cotton condenser after the cotton lint has left the cotton gin and before it has been arranged in bales.

Another object of this invention is the provision of means of the type mentioned which does not require the consumption of power in addition to that normally required by the condenser.

The following description, considered together with the accompanying drawings will fully disclose this invention, its construction, arrangements and combinations of parts, and further objects and advantages thereof will be apparent.

In the drawings:

Figure 1 is a plan view of a cotton condenser with the cover of the housing removed showing an illustrative embodiment of our invention therein.

Figure 2 is an end elevation of Figure 1 with part of the wall of the housing broken away.

Figure 3 is an enlarged section along the line 3—3 of Figure 1.

Figure 4 is a plan view similar to that of Figure 1 showing an alternative embodiment of this invention.

Figure 5 is a section along the line 5—5 of Figure 4.

Figure 6 is a section along the line 6—6 of Figure 4.

Referring with more particularity to the drawings in which like reference characters designate like parts, the letter A designates the casing or housing of a cotton condenser of the type well known in the art, having a perforated cylinder B disposed on a powered shaft b; a compression roller D co-acting with said cylinder B; a lint flue

transition C for delivering the air-borne lint cotton to the condenser; and a lint slide E constituting the material outlet from the condenser.

In the first illustrative embodiment of this invention (Figures 1, 2, and 3), parallel imperforate bands 1, 1 characterized by the fact that they are non-collective of lint cotton are secured about the cylinder B in spaced relation. Supporting strips 2, 2 are disposed with a small clearance over said bands 1, 1, respectively. One of the ends of each of the strips 2, 2 is secured to blocks 3, 3, respectively, and the other ends of said strips are secured to the floor 4 of the lint flue transition C.

Arcuated partitions 5, 5 having an outer contour substantially ogee, are secured by any suitable means on the members 2, 2 between the roller D and the floor 4, substantially as shown. On the sides of said partitions 5, 5 flexible flap seals 6, 6, 6, 6 are attached extending outwardly beyond the edges of the supporting members 2, 2 and rest on the periphery of the bands 1, 1.

After the mass of air-borne lint cotton fibers enters the condenser from the transition C, it is separated by the partitions 6, 6 before striking the cylinder B and being compressed into bats by the roller D. One of these bats may be regarded as the sample bat. The flap seals 6, 6, 6, 6 prevent the escape of the lint laden air currents into the clearance between the bands 1, 1, and the supporting strips 2, 2. The supporting strips 2, 2, also act as fillers so that the aerodynamic resistance at these points is made substantially equal to or greater than the aerodynamic resistance along the lint filled spaces between the bottom of the roller D and the cylinder B. The purpose of this is so that the discharged bats are definitely separated from each other without any inter-felting of the lint fibers between the edges of the bats.

Referring with more particularity to Figures 4, 5 and 6 which show a modification of this invention, the partitions 5, 5 instead of being supported on strips 2, 2 are simply secured to the floor 4 of the transition C in cantilever fashion. In addition to this the roller D is provided with fixed concentric collars 7, 7 operating in rolling contact with the bands 1, 1. The collars 7, 7 contacting the bands 1, 1, fill the space normally existing at these points between the roller D and the cylinder B, for the purpose of diverting the air-borne lint at these points. As a result the bats, upon discharge, are definitely separated from each other without any inter-felting of the lint fibers between the edges of said bats.

Having thus described our invention, we claim:

- 5 1. In a cotton condenser having a screen condenser cylinder, a compression roller co-acting therewith, and an intake flue transition; means for producing a sample bat of lint cotton, said means comprising parallel imperforate bands secured concentrically about the condenser cylinder, stationary partition walls non-collective of 10 lint cotton supported over said bands on the intake side of the condenser between said compression roller and the floor of the inlet flue transition, there being a small clearance between said walls and said bands, and flexible sealing members attached to the sides of said walls extending outwardly and slidably contacting said bands.
- 15 2. In a cotton condenser having a screen condenser cylinder, a compression roller co-acting therewith, and an intake flue transition; means for producing a sample bat of lint cotton, said means comprising parallel imperforate bands concentrically secured to the condenser cylinder, parallel imperforate collars concentrically secured to the compression roller in rolling contact 20 with said bands, stationary partition walls non-collective of lint cotton supported over said bands 25

on the intake side of the condenser between the compression roller and the floor of the inlet flue transition, there being a small clearance between said walls and said bands, and flexible flap members attached to the sides of said walls extending outwardly and slidably contacting the peripheries of said bands.

5 10 15 20 25 3. The combination with a cotton condenser having a housing, a rotatable screen cylinder, compression rollers, an outlet opening and an inlet flue transition; of a plurality of spaced encircling imperforate band-like areas on the periphery of the screen cylinder disposed parallel to the ends of said cylinder, arch-shaped partitions having substantially an ogee outer contour, 15 said partitions being superposed vertically above said imperforate areas and extended from the compression rollers in diminishing height to the floor of the lint flue transition, means for supporting said partitions in spaced relation to the 20 outer surfaces of said imperforate cylinder areas and said compression rollers, and flexible flaps extended from the lower edges of said partitions to the surfaces of said imperforate cylinder areas.

GEORGE E. GAUS.

VICTOR L. STEDRONSKY.
